(57) **CLAIM**

The ornamental design for a pivotable headlight, as shown and described.

DESCRIPTION

FIG. 1 is a view in perspective of a design of my pivotable headlight;

FIG. 2 is a front view thereof;

FIG. 3 is a rear view thereof;

FIG. 4 is a first side view thereof;

FIG. 5 is a second side view thereof;

FIG. 6 is a plan view thereof; and,

FIG. 7 is a bottom view thereof.

The broken lines shown throughout the views are features that form no part of the ornamental design.
